UNITED STATES PATENT OFFICE.

WILLIAM F. A. BUEHNER, OF NEWARK, NEW JERSEY.

CLAMP FOR ROWBOAT-MOTORS.

1,204,739.

Specification of Letters Patent. Patented Nov. 14, 1916.

Application filed February 15, 1916. Serial No. 78,347.

To all whom it may concern:

Be it known that I, WILLIAM F. A. BUEHNER, residing at Newark, in the county of Essex and State of New Jersey, have invented certain new and useful Improvements in Clamps for Rowboat-Motors, of which the following is a specification.

This invention relates to an improved form of clamp by the use of which detachable rowboat motors may be quickly and firmly attached to or released from the backboard of rowboats or the like.

The principal object of the invention is to provide a simple, practical and efficient clamp for this purpose.

A more specific object is to provide a clamp which will operate to throw into clamping position a clamping member of considerable size at a single throw or turn 20 of a lever, as distinguished from the two independently operable and spaced thumb screws heretofore used for this purpose, and to provide means comprised in the clamp for retaining it locked in its clamped position.

Other objects and aims of the invention, more or less specific than those referred to above, will be in part obvious and in part pointed out in the course of the following 30 description of the elements, combinations, arrangements of parts and applications of principles, constituting the invention; and the scope or protection contemplated will be indicated in the appended claims.

In the accompanying drawings which are to be taken as a part of this specification, and in which I have shown a merely preferred form of embodiment of the invention: Figure 1 is a side elevational view of 40 a device constructed in accordance with the principles of this invention; and Fig. 2 is a front elevational view of the clamp shown in Fig. 1.

Referring to the drawings for a detailed 45 description of the particular structure illustrated therein, the reference character L indicates a frame formed with a pair of spaced legs 1 adapted to rest flat against the rear surface of the backboard of the boat. Portions, as 2, of this frame are bent outwardly so as to accommodate the stern-post of the boat.

In the drawings the backboard is illustrated in dotted lines by the reference numeral 3 and the stern-post by the reference 50 numeral 4.

At the upper ends of the opposite arms of the legs 1 suitable bearing members 5 are formed for pivotally connecting the same to the motor and propeller wheel carrying shaft, indicated collectively in dotted lines by the reference numeral 6. Projecting forwardly from each of the legs 1, near the upper ends thereof are portions 7, said portions being connected together by a brace 60 member 8 and having their forward ends turned downwardly, as at 9. The downturned portions 9 are each apertured to support a cross shaft 10 about which is pivotally mounted a pair of clamp members 70 11 and 12. The clamp member 11 is formed with an operating handle 13 projecting upwardly therefrom and being turned in a direction toward the clamp member 12. The clamp member 12 is formed with an operating handle 14 projecting upwardly therefrom and turned toward the clamp member 11. The adjacent ends of the operating handles 13 and 14 are telescopically connected together, the handle 13 being formed 80 with a recess 15 into which the end of the operating handle 14 slidably engages. A hand grip 16 is provided upon the part 13.

By swinging the hand grip 16, it is apparent that the motion thereof will be transmitted equally to each of the clamp members 11 and 12.

A compression spring 17 is positioned about the shaft 10 intermediate the clamp members 11 and 12 and exerts a pressure 90 serving to hold the clamp members in resilient engagement with the inner surfaces of the downturned portions 9 of the frame.

The opposing surfaces of the clamping members of the portions 9 of the frame are 95 provided with coöperating teeth 18 thereon encircling the shaft 10 adapted to retain the clamping members in any position into which they may be moved by the handle grip 16. These teeth preferably are arranged so as to permit easy travel of the handle grip in one direction but to prevent movement thereof in the opposite direction. When it is desired to move the clamping members in the opposite direction they must be manually drawn together against the pressure of the spring 17 and for this purpose the operating handle 14 is provided with a finger grip 19 adjacent the handle grip 16 through the medium of which the operator may readily move the clamping members toward each other by gripping the 100 105 110

handle grip 16 and finger grip 19 tightly in his hand.

A clamping plate 20 extends across the full width of the frame L and is resiliently supported upon a pair of pins 21 carried at the lower ends of the portions 9. Suitable springs 22 are arranged for urging the pins backwardly to normally retain the clamping plate 20 out of contact with the 10 surface of the backboard of the boat.

In order that rotation of the clamp members 11 will operate to move the clamping plate into engagement with the surface of the backboard of the boat, said clamping 15 members are formed with eccentric or cam portions 23 shaped so that when the handle grip is in its raised position, as shown by the full lines in Fig. 1, the clamping plate will be furthest removed from the backboard 20 of the boat, and so that the clamping plate will be moved gradually and forcefully toward the surface of the backboard as the handle grip is swung downwardly.

From the above description it will be apparent that the lower portion of the frame L will serve as one of the clamping members while the clamping plate 20 serves as the other. The operator has merely to place the frame in the position with the 30 lower part of the frame L resting against the rear surface of the backboard of the boat and the forwardly extending portions 7 resting upon, or nearly upon the upper edge of the backboard, whereupon he swings 35 the operating handle downwardly to cam the clamping plate firmly against the backboard, the teeth 18 clicking past each other. The parts will remain in clamped position until he moves the clamping members to disengage the teeth 18 and allow the operating 40 handle to swing upwardly.

As many changes could be made in this construction without departing from the scope of the following claims, it is intended 45 that all matter contained in the above description or shown in the accompanying drawing shall be interpreted as illustrative only and not in a limiting sense.

Having thus described my invention what 50 I claim as new and desire to secure by Letters Patent is:

1. A clamp for rowboat motors or the like, comprising opposing clamp members, cam means for operating upon one of said 55 clamp members at spaced points in the length thereof, and a single operating handle for said cam means.

2. A clamp for rowboat motors or the like, comprising opposing clamp members, a

pair of cam members spaced apart and operatively engaging one of said cam members at spaced points in the length of said mentioned clamp member, operating handles formed upon said cam members projecting toward each other, and a single handle grip 60 65 by means of which both said operating handles may be controlled.

3. A clamp for rowboat motors or the like, comprising opposing clamp members, a pair of cam members spaced apart and operatively engaging one of said clamp members at spaced points in the length of said mentioned clamp member, operating handles formed upon said cam members projecting toward each other, toothed means for retaining the cam members against accidental movement, and because of which the cam members move relatively to each other when said cam members are operated by said operating handles, and said operating handles 70 75 being telescopically connected together to permit said cam members to move relatively to each other and a single handle grip for both said operating handles.

4. A clamp for rowboat motors or the like, comprising opposing clamp members, a plurality of operating members engaging one of said clamp members at spaced points upon said mentioned clamp member operable to move said mentioned clamp member into clamping position, and means for moving said operating members in unison. 80

5. A clamp for rowboat motors or the like, comprising opposing clamp members, resilient means for resiliently urging one 85 of said clamp members away from clamping position, a shaft, a pair of operating members pivotally supported upon said shaft having cam surface portions engaging said mentioned clamp member at spaced points 90 thereon, control means for rotating said operating members whereby to cause the cam faces thereof to force the mentioned clamp member into clamping position, toothed means for retaining at least one of said operating members in a desired position of rotation about the shaft, said operating member being slidable upon the shaft, and resilient means adapted to permit sliding movement 100 of the operating member along the shaft to 105 render the toothed means operative.

In testimony whereof I affix my signature in the presence of two witnesses.

WILLIAM F. A. BUEHNER.
